UNITED STATES PATENT OFFICE.

JOHN BEISWANGER, OF STEUBENVILLE, OHIO, ASSIGNOR TO GILL BROTHERS COMPANY,
OF STEUBENVILLE, OHIO, A CORPORATION OF WEST VIRGINIA.

DESIGN FOR A BAKING-DISH.

52,692.

Specification for Design.

Patented Nov. 19, 1918.

Application filed May 6, 1918. Serial No. 232,942. Term of patent 7 years.

To all whom it may concern:

Be it known that I, JOHN BEISWANGER, a citizen of the United States of America, and resident of Steubenville, county of Jefferson, State of Ohio, have invented a certain new, original, and ornamental Design for a Baking-Dish, of which the following is a specification.

In the accompanying drawings I have illustrated a baking-dish constructed in accordance with my invention.

Figure 1 is an elevation of the dish in upright position, looking at it from one side; and

Fig. 2 is a bottom plan of the same.

The dish embodying the invention is a baking-dish of transparent material and of the type generally known as a custard cup, though used for baking various articles of diet. It is of cup-like outline, being circular in plan and having side walls 2, propor-

tionately of considerable depth. The outer surface of the walls is ornamented with vertically extending Doric flutes 3 which at their upper ends meet and combine with the curved surface 4 of the top peripheral edge of the side walls. At the bottom they shade into the curved peripheral surface 5 of the rounded bottom corner.

The bottom of the dish as shown is ornamented with radial flutes 6, joining at their outer ends with the peripheral surface 5.

Having thus described and illustrated my invention, I claim:

The ornamental design for a baking-dish, substantially as shown and described.

Signed by me at Steubenville, Jefferson county, Ohio, this 4th day of May, 1918.

JOHN BEISWANGER.
